HOUSING FOR VENDING MACHINE

Harold M. Schaeef, Chicago, Ill., assignor to Victor
Vending Corporation, Chicago, Ill., a corporation of Illinois

Application December 2, 1950, Serial No. 13,237

Term of patent 14 years

(Cl. D52—3)

To all whom it may concern:

Be it known that I, Harold M. Schaeef, a citizen of the United States and resident of Chicago, in the county of Cook and State of Illinois, have invented a new, original, and ornamental Design for a Housing for Vending Machine, of which the following is a specification, reference being had to the accompanying drawing, forming a part thereof.

Fig. 1 is a perspective view of the housing for vending machine, showing the dominant portions of my new design in full lines.

Fig. 2 is a side elevational view thereof.

Fig. 3 is a top plan view thereof.

I claim:

The ornamental design for a housing for vending machine, substantially as shown and described.

HAROLD M. SCHAEF.
